CATHODE STRUCTURE

Polykarp Kusch, New York, N. Y., assignor to the
United States of America as represented by the
Secretary of War

Application July 9, 1945, Serial No. 604,072

5 Claims. (Cl. 250—27.5)

1

This invention relates in general to cathodes and more particularly to such cathodes as are applicable to magnetron tubes.

As magnetrons are used for shorter and shorter wavelengths, the efficiency becomes very low. This low efficiency is in part due to the "bad" electrons emitted from the cathode. "Bad" electrons are those which are accelerated by the radio frequency field between cathode and anode, and thus absorb energy from this field. Some of these electrons have a path such that they turn around and bombard the cathode with considerable energy, causing what is known as back-heating of the cathode.

Under conditions of very short wavelength, it is necessary, because of the back-heating, to use a comparatively massive cathode for proper cooling. Also, sparking of magnetron cathodes is a common cause of cathode failure, and it has been found that an irregular cathode surface delays such a failure. Under sparking conditions it is also desirable to provide a large amount of coating of electron-emitting material on the cathodes in order that sufficient thermionic emission be available after sparking occurs.

Among the objects of this invention, therefore, are:

1. To provide a cathode structure applicable to magnetrons;
2. To provide such a cathode having increased durability with respect to electron bombardment; and
3. To provide such a cathode having reduced susceptibility to failure under sparking conditions.

In accordance with the present invention, there is provided a sleeve-like cathode structure in which the outer surface of the cathode has grooves in both the longitudinal and the circumferential directions. Two heavy supporting tabs are welded to massive cathode supports for efficient heat conduction.

This invention will best be understood by reference to the drawings, in which:

Fig. 1 illustrates a cross-sectional view and side-view of the blank used for construction of the cathode according to this invention;

Fig. 2 illustrates a cross-sectional view of the central portion of the blank with the circumferential grooves, and a portion of the mandrel used for turning the blank;

Fig. 3 illustrates the same portion of the blank and mandrel of Fig. 2 after a knurling operation;

Fig. 4 illustrates the plan and side view of a tab used for supporting the cathode;

2

Fig. 5 is a perspective view of the cathode and cathode leads in assembled form.

Referring now to the description of the cathode and to one desirable manufacturing process, Fig. 1 illustrates a cut-away section of a flanged hollow cylinder which is used as a blank for construction of the cathode, flanges 11 and 15 acting as two "hats" for preventing the "Gadarene effect" in magnetrons. In one embodiment of the invention the material used for the cathode was pure nickel.

Circumferential grooves are then cut in the blank by mounting it over a lathe mandrel 16, the details of the grooves 12 being illustrated in Fig. 2. In an exemplary embodiment of this invention, the grooves were 0.0075 inch wide, with the distance between grooves being 0.0075 inch. With the blank still in the lathe and on mandrel 16, the cathode surface is then rolled by a fine straight knurl in order to produce longitudinal grooves 18 illustrated in Fig. 5, which are similar to the circumferential grooves 12. Fig. 3 illustrates the dovetail shape of the circumferential grooves 12 after 25 knurling. It is seen that the bottoms 12 of the grooves are wider than the tops 14, the dovetail grooves thus acting as anchoring means for an oxide coating 20, Fig. 5, sprayed or painted over the dovetailed and knurled surface of the cathode cylinder 10.

After the first rotation of the cathode during the knurling operation, it is not important that the knurling tool mesh with previously made indentations for good cathode operation. Knurling 35 in this manner increases slightly the outside dimension of the cathode. In one embodiment, the outside diameter was increased 0.003 inch from an original value of 0.11 inch.

A supporting tab 20 which could be used in conjunction with the present cathode is illustrated in Fig. 4. These tabs have their circular portions supporting each end of the cathode as illustrated in Fig. 5, and are welded to comparatively massive cathode support leads 22 and 24, 45 which extend through a glass seal 26 to a point outside the tube where cooling fins 28 and 29 may be attached to the cathode rods 22 and 24 for a more effective dissipation of heat.

With the small compartments 30 that are 50 formed in the cathode structure by virtue of the grooving and knurling operations, it can be seen from Figs. 3 and 5 that unusually large amounts of coating material 32 may be retained by the cathode. Also, this irregular surface is of such 55 a contour as to bind or to anchor the cathode

coating 32 more firmly to the cathode, thus delaying the failure due to sparking.

Carrying away of the cathode heat caused by back-heating is facilitated by the use of the comparatively massive cathode supporting tabs 20 and 20-A shown in Figs. 4 and 5.

The cathode in its assembled form is illustrated in Fig. 5. The grooved and knurled portion of the cathode is illustrated at 30, and the oxide coating at 33, which is either sprayed or painted with a brush on portion 30 of the cathode. Tabs 20 and 20-A are brazed to the hats 11 and 15, and to the tungsten rods 22 and 24. The heater coil, inserted into the hollow portion of cylinder 10 has its upper end 32 brazed to tab 20 and hat 11, while its lower end 34 is connected to a jumper 38 an outer conductor 36 of the concentric line formed by this conductor with tungsten rod 24, the two being insulated from each other by an insulating sleeve 39. Conductor 36 is connected to a rod 40 which protrudes through the glass seal 26 for completing the external connections of the heater coil. As disclosed in my co-pending application 604,073, now Patent No. 2,437,880, filed simultaneously with the filing of this application, the dimensions of the tungsten rods 22 and 24 are made to hold the cathode in concentric relationship with respect to the anode when the magnetron reaches the operating thermal equilibrium.

The advantages of the disclosed cathode structure are: Large amount of the oxide material 32 which is anchored to cylinder 10 and thus cannot be loosened from the cylinder because of cyclic heating and cooling of the cathode produced by the electrons whose curvilinear paths in the interaction zone of the magnetron are such as to lead them back to the cathode during the duty cycles of magnetron. The overheating of the cathode is prevented by making the cathode blank of massive construction so that it has relatively large calorific inertia, and by dissipating excess of heat through the relatively thick walls of the cathode cylinder 10, tabs 20, 20-A, massive tungsten rods 22, 23, and radiators 28 and 29. Prior to the advent of the disclosed cathode the X- and K-band magnetrons had hardly any useful life because of short life of cathodes.

While there has been described what is at present considered the preferred embodiment of the invention, it will be obvious to those skilled in the art that various changes and modifications may be made therein without departing from the invention, and it is, therefore, aimed in the appended claims to cover all such changes and

modifications as fall within the true spirit and scope of the invention.

I claim:

1. A cathode structure comprising a hollow, flanged metallic cylinder, dovetailed grooves around the outer surface of said cylinder, knurled grooves crossing said dovetailed grooves, and an electron-emitting oxide coating anchored to said cylinder by means of said grooves.

5 2. A cathode structure as defined in claim 1 which also includes two metallic tabs, each having a washer portion and a bar portion, the washer portion of each tab being brazed to the outer circular surface of the respective flange, and a metallic rod, connected to each bar portion of said tab, for mechanically supporting said cathode and for completing the electrical circuit of said cathode.

10 3. A cathode structure comprising a hollow, metallic, machined cylinder, an integral flange at each end of said cylinder, dovetailed ring-grooves around the outer surface of said cylinder, straight knurled grooves at right angles to said ring-grooves, and an electron-emitting oxide layer anchored to said cylinder by said ring-grooves and said knurled grooves.

15 4. A cathode structure as defined in claim 3 which further includes metallic radiators conductively connected to said cylinder for cooling said cylinder during the operating cycle of said cathode.

20 5. A cathode structure comprising a hollow, metallic cylinder, an integral flange at each end of said cylinder, dovetailed grooves around the outer surface of said cylinder and additional grooves crossing said dovetailed grooves, a metallic member brazed to each flange, said metallic member having a metallic arm radially extending away from said flange through a glass seal, and radiating surfaces at the outer end of each member for cooling said cylinder during the operation of said cathode.
